Application April 21, 1953, Serial No. 24,610

Term of patent 7 years

(Cl. D57—1)

To all whom it may concern:

Be it known that I, Nathan Newman, a citizen of the United States and a resident of the city, county, and State of New York, have invented a new, original, and ornamental Design for an Ophthalmic Mounting or the like, of which the following is a specification, reference being had to the accompanying drawing, forming a part thereof, in which:

Fig. 1 is a front elevational view of an ophthalmic mounting showing my new design; and

Fig. 2 is a top plan view thereof.

The dominant features of my new design are shown in solid lines.

I claim:

The ornamental design for an ophthalmic mounting or the like, as shown and described.
